COMBINATION TOOTHPASTE DISPENSING
CABINET AND TOOTHBRUSH HOLDER

Reuben B. Lambert, Terryville, Conn.

Application September 24, 1956, Serial No. 43,055

Term of patent 3½ years

(Cl. D4—3)

Fig. 2

Fig. 1 of the drawing represents a perspective view of the combination toothpaste dispensing cabinet and toothbrush holder, showing my new design.

Fig. 2 shows a perspective view of the same in closed condition.

I claim:

The ornamental design for a combination toothpaste dispensing cabinet and toothbrush holder, substantially as shown.
